REARVIEW MIRROR

Theodore E. Brown, Chicago, Ill.

Application June 2, 1952, Serial No. 20,001

Term of patent 14 years

(Cl. D14—6)

To all whom it may concern:

Be it known that I, Theodore E. Brown, a citizen of the United States of America, residing at Chicago, county of Cook, and State of Illinois, have invented a new, original, and ornamental Design for Rearview Mirror, of which the following is a specification, reference being had to the accompanying drawing, forming part thereof.

Figure 1 is a side elevational view of a rearview mirror, showing my new design.

Fig. 2 is a side elevational view of the opposite side of the device shown in Fig. 1 but showing the mirror turned 90° from the position shown in Fig. 1.

Fig. 3 is a top elevational view of the device of Fig. 1 but showing the handle turned slightly from the vertical plane.

Fig. 4 is an end elevational view of the device of Fig. 2 but showing the handle turned slightly from the vertical plane.

Fig. 5 is an end elevational view of the device of Fig. 1 but showing the handle turned slightly from the vertical plane.

I claim:

The ornamental design for a rearview mirror, as shown.

THEODORE E. BROWN.
